United States Patent Office.

WILLIAM P. UHLINGER, OF PHILADELPHIA, PENNSYLVANIA.

Letters Patent No. 94,928, dated September 14, 1869.

IMPROVED RUSTIC SETTEE.

The Schedule referred to in these Letters Patent and making part of the same.

To all whom it may concern:

Be it known that I, WILLIAM P. UHLINGER, of Philadelphia, in the county of Philadelphia, and State of Pennsylvania, have invented a new and valuable Improvement in Rustic Settees; and I do hereby declare that the following is a full, clear, and exact description of the construction and operation of the same, reference being had to the annexed drawings, making a part of this specification, and to the letters and figures of reference marked thereon.

Figure 1, of the drawings, is an end view of my settee;

Figure 2 is a rear view; and

Figures 3 and 4 are details.

My invention relates to rustic settees for garden-walks, piazzas, and other appropriate places; and consists, mainly, in the construction and novel arrangement of devices, whereby the slats forming the back and seat of the settee are made removable from the cast-iron supporting standards, subserving, in this way, important purposes of economy and convenience in transportation and storage.

The letter *b*, of the drawings, designates a slat of wood or other suitable material, used to form the seat and back of my settee, the same being secured at the ends to cast-iron standards *a*, by devices hereinafter described.

a represents the cast-iron standard, of any suitable design, having its upper edge *a'* curved, to give such shape as may be desired to the back and seat of the settee.

The slats *b* are attached to the bar *a'* by the screws *g*, passing into and through notches formed in the lugs *f*, cast on the outer side of the bar *a'*, as shown.

Or the slats may be attached by inserting into slanting apertures bored therein, the pins *e* cast on the bar *a*, and slanting outward.

In order to render either attachment secure, and to brace up firmly the standards *a*, the locking-eccentric *l* is employed.

This eccentric *l* turns about the head of the screw *h*, fastened into the slat *b*. This eccentric has in its outer surface two grooves, one at right angles to the other, which are used as purchases in turning the same, by means of a screw-driver or other suitable implement.

When the full side of the eccentric *l* is brought

against the bar *a'*, the lugs *f* are forced against the screws *g* tightly, thus securing and bracing the attachment. Or, in the other modification, the pressure of the full side of the eccentric *l* forces the pins *e* tightly into their slanting receptacles, thus in a similar manner securing and bracing the attachment.

Generally, three eccentric blocks are used for each standard, one being placed under one of the front slats of the seat and attached thereto, a second to one of the slats near the lower part of the back, and the third to a slat near the top of the back.

It is apparent that when it is desired to take the settee apart, the simple turning of the eccentric *l* will cause the connecting-devices to become loose and easily separated.

Sometimes, instead of the eccentric lock, a short brace, *e*, may be used, abutting against the bar *a'*, and against a shoulder formed in the slot, as shown at *m*, and held in place by means of the screw *d*. This modification of the locking-device is made removable by means of the screw *d*. For ordinary use, I prefer the eccentric *l*, first described.

What I claim as my invention, and desire to secure by Letters Patent, is—

1. The eccentric lock *l*, when arranged to operate with reference to the slanting pins *e*, substantially as and for the purposes specified.

2. The eccentric lock *l*, when arranged to operate with reference to the lugs *f* and screws *g*, substantially as and for the purposes described.

3. The brace-lock *e*, when arranged to operate with the slanting pin *e*, substantially as and for the purposes specified.

4. The brace-lock *e*, when arranged to operate with the lugs *f* and screws *g*, substantially as and for the purposes set forth.

5. In combination with the rustic settee herein described, the slanting pin *e*, and the modifications *f* and *g*, constructed and arranged substantially as specified.

In testimony that I claim the above, I have hereunto subscribed my name, in the presence of two witnesses.

W. P. UHLINGER.
